UNITED STATES PATENT OFFICE.

ANNA WOHLERT CHRISTENSEN, OF DETROIT, MICHIGAN.

BOBBIN-HOLDING ATTACHMENT FOR SEWING-MACHINES.

No. 890,605.

Specification of Letters Patent.

Patented June 16, 1908.

Application filed July 1, 1907. Serial No. 381,777.

To all whom it may concern:

Be it known that I, ANNA WOHLERT CHRISTENSEN, a citizen of the United States of America, residing at Detroit, in the county of Wayne and State of Michigan, have invented 5 certain new and useful Improvements in Bobbin-Holding Attachment for Sewing-Machines, of which the following is a specification, reference being had therein to the accompanying drawings.

It is the object of the invention to provide means for utilizing thread previously wound upon a bobbin for the upper thread of a machine and without the necessity of rewinding 15 upon the spool.

To this end, the invention consists in the novel construction of a bobbin holder which may remain in permanent attachment to the machine in a position for use, as above described, and without interference with the ordinary operation of the machine.

In the drawings—Figure 1 is an elevation of my attachment; Fig. 2 is a perspective view illustrating a modified construction; 25 and Fig. 3 is a side elevation thereof.

A is the spool supporting post of a sewing machine and B indicates in dotted lines a spool thereon. My invention comprises a bobbin holding frame C, which is swiveled 30 upon the post A, as by the eye portion a, and has lateral portions b and b' of sufficient length to clear the radius of the spool. This frame is preferably made of wire, the eye portion a being formed by a coil, and the laterally projecting portions b b' being formed at the opposite ends thereof. The portion b is further provided with an upwardly projecting portion c terminating in an outwardly projecting portion d. At the end of this portion d is a downwardly projecting pintle e and a corresponding upwardly projecting pintle f is formed at the outer end of the arm b'. These two pintles e and f are adapted for insertion in the opposite ends of a tubular bobbin, and the frame C has sufficient resiliency 45 to permit of springing the pintles apart for engagement and disengagement.

In the modification illustrated in Fig. 2, the device is adapted for holding a solid shank bobbin. For this purpose, the pintles e and f are omitted and in place thereof socket bearings g for the pointed ends of the

bobbin are formed in the members b and b'.

With either construction, the frame C is adapted to be left in permanent engagement 55 with the post A without interference with the normal use of said post in supporting a spool of thread, this being for the reason that the radial arms b and b' are of greater length than the radius of the largest spool to be placed 60 upon the post. Whenever it is desired to use the thread on a bobbin for the upper thread of the machine, this bobbin is engaged either with the sockets g or the pintles e and f according to the character of the bobbin 65 itself, after which the machine may be threaded in the usual way and in use the thread reeled from the bobbin as it would be reeled from the spool on the post A.

What I claim as my invention is:

1. The combination with a bobbin and the spool-supporting post of a sewing machine, of a bobbin holder formed of wire bent to form an eye portion for engaging the spool-supporting post and to form laterally-extending arms, an upwardly-extending portion on one of the arms, an outwardly-extending portion on said upwardly-extending portion, and means on said outward extension and the other one of said arms for engaging the bobbin.

2. The combination with a spool supporting post of a sewing machine and a bobbin, of a bobbin holder formed of wire bent to form an eye portion a for engaging with the spool supporting post, the arms b and b' projecting outwardly therefrom, the upwardly extending portion c on the arm b and the outwardly extending portion d therefrom and oppositely projecting pintles e and f, substantially as and for the purpose described.

3. The combination with a bobbin, of a holder therefor made of wire bent to form an eye for engaging the spool post of a sewing machine, adapted to fit underneath the spool and shaped so as to provide clearance for the revolving of the spool.

In testimony whereof I affix my signature in presence of two witnesses.

ANNA WOHLERT CHRISTENSEN.
